UNITED STATES PATENT OFFICE.

EDWIN Q. BANGS, OF RACINE, WISCONSIN, ASSIGNOR TO HAMILTON BEACH MFG. CO.,
OF RACINE, WISCONSIN, A CORPORATION OF WISCONSIN.

MOTOR MOUNTING.

Application filed May 20, 1926. Serial No. 110,360.

This invention relates to improvements in motor mountings, particularly adapted for attaching electric motors to sewing machine heads for driving the machine hand wheels.

5 It is one of the objects of the present invention to provide a motor mounting for a sewing machine head to so hold the motor that the pulley wheel thereof will be yieldingly held in frictional engagement with the
10 machine hand wheel.

A further object of the invention is to provide a motor mounting of the class described non-removably engaging both the head and the motor.

15 A further object of the invention is to provide a motor mounting of the class described adapted for ready attachment to the side of the head of any of the well-known makes of sewing machines.

20 A further object of the invention is to provide a motor mounting for sewing machine heads which is of very simple construction, is inexpensive to manufacture, is strong and durable, and is well adapted for the purpose set forth.

25 With the above and other objects in view the invention consists of the improved motor mounting and its parts and combinations as set forth in the claims, and all equivalents thereof.

30 In the accompanying drawing in which the same reference characters indicate the same parts in both of the views:

35 Fig. 1 is an end view of a sewing machine head having an electric motor attached thereto by means of the improved motor mounting; and

Fig. 2 is a side view thereof.

40 Referring now more particularly to the drawing, it will appear that the numeral 5 indicates the head portion of a sewing machine having a hand wheel 6 mounted at its end.

45 Adapted to be secured to the side of the head is a small flat type electric motor 7 and

the securing means or mounting comprise a plurality of legs 8, 9 and 10, bent as shown, and formed of spring steel. The inner ends of all of the legs are secured to the motor by screws, while the outer ends of only the legs 50 8 and 10 are attached to the head by screws. All of the legs are of such a length that the pulley wheel 11 of the motor yieldingly bears against the hand wheel to frictionally drive the same. The yieldability of the legs and 55 the free end portion of the side leg 9 allows the motor to give when necessary to compensate for irregularities in the motion of the hand wheel.

From the foregoing description it will be 60 seen that the improved motor mounting is of very simple and novel construction and is well adapted for the purpose described.

What is claimed as the invention is:

1. The combination with a sewing machine head having a hand wheel, of a motor having a pulley wheel adapted for yielding frictional engagement with the periphery of the hand wheel, a yieldable strip secured to the lower portion of the motor and to a lower 65 portion of the head, a yieldable strip secured to the upper portion of the motor and to an upper portion of the head, and a yieldable strip secured to an intermediate portion of the motor and non-fixedly bearing against an 70 75 intermediate portion of the head.

2. The combination with a sewing machine having a hand wheel, of a motor having a pulley wheel adapted for yielding frictional engagement with the periphery of the hand 80 wheel, a plurality of thin yieldable members interposed between the motor and the sewing machine head at different points and being secured both to the head and to the motor, and another thin yieldable member secured 85 only to the motor and non-fixedly bearing against the head.

In testimony whereof, I affix my signature.

EDWIN Q. BANGS.
